United States Patent Office

Des. 188,813
Patented Sept. 13, 1960

188,813

PHONOGRAPH CABINET

Lyndon A. Durant, Chicago, Ill., assignor to United Music Corporation, Chicago, Ill., a corporation of Illinois

Filed June 16, 1958, Ser. No. 51,374

Term of patent 14 years

(Cl. D56—4)

FIG. 1

FIG. 3

Fig. 1 is a front perspective view of a phonograph cabinet, showing my new design.

Fig. 2 is a top plan view thereof.

Fig. 3 is a side view thereof.

The dominant features of the design are shown in full lines.

I claim:

The ornamental design for a phonograph cabinet, as shown and described.
